UNITED STATES PATENT OFFICE.

BENJAMIN F. HUGHES AND FERDINAND A. PFEIFER, OF SPRINGFIELD, OHIO; SAID PFEIFER
ASSIGNOR TO SAID HUGHES.

DOOR-FASTENER.

No. 883,814.

Specification of Letters Patent.

Patented May 26, 1908.

Application filed May 6, 1907. Serial No. 371,951.

To all whom it may concern:

Be it known that we, BENJAMIN F. HUGHES and FERDINAND A. PFEIFER, citizens of the United States, residing at Springfield, in the county of Clark and State of Ohio, have invented certain new and useful improvements in Door-Fasteners, of which the following is a specification, reference being had therein to the accompanying drawings.

The present invention relates to door fasteners, and the object of the invention is to provide a fastener, by means of which any ordinary door can be quickly and securely fastened; and further, to provide such a fastener which will be at the same time light and strong and which can be readily carried about the person.

With these objects in view our invention consists in certain novel features of construction hereinafter to be described, and then more fully pointed out in the claim.

In the accompanying drawings, Figure 1 is a perspective view of a door fastener embodying our invention; Fig. 2 is a sectional view of a portion of a door and door jamb, showing our invention in position thereon; and Fig. 3 is a longitudinal sectional view, taken centrally through the fastener.

In these drawings we have illustrated the preferred form of our invention, which, as herein shown, consists of a plate 1 having near its forward end an outwardly extending projection adapted to engage the face of the door jamb. This projection is preferably pointed or sharpened, and, as here shown, consists of a tapering rib 2 extending across the face of the plate 1 and divided to form a plurality of teeth, thereby facilitating its entrance into the substance of the door jamb. At a point in the rear of the projection 2 the plate 1 is provided with a shoulder 3, which is preferably formed by providing the plate 1 with a thickened portion 4. This shoulder is on the same side of the plate and extends in the same direction as the projection 2 and is adapted to engage the edge of the door jamb when the projection is in engagement with the face thereof. The plate 2 is provided with an aperture 5 near said shoulder and preferably extending through the thickened portion, as herein shown. The part of plate 1 in the rear of said thickened portion is preferably reduced in size to form a convenient handle 6, which may be pro-

vided at its rear end with a ring 7, to which is secured one end of a chain 8 having at its opposite end a pin 9 adapted to fit within the aperture 5 of the plate 1 and to extend beyond the plate 1 on one or both sides thereof, thus forming a stop adapted to engage the door and prevent the outward movement of the same.

In order to prevent the corner of the door from engaging the end of the plate and causing the projection 2 to twist or turn in the jamb, thus tearing and defacing the same, we extend the end of the plate a short distance beyond the projection 2 and round off this projecting end, as shown in Fig. 1, and bevel this extension of the plate on the side opposite the side having the projection 2, as shown in Fig. 3. This construction prevents all turning or twisting of the plate and projection and prevents the plate from being so engaged by the door as to crowd the projection out of its seat.

The operation of the device will be obvious from the foregoing description. When it is desired to fasten a door, the fastener is placed against the face of the door jamb with the shoulder 3 in engagement with the edge thereof and held in that position by means of the handle 6. The door is then forced shut, and, as the edge of the door presses against the rear side of the plate 1, the sharpened projection 2 is forced into the substance of the door jamb, as shown in Fig. 2 of the drawings, thus allowing the door to be completely closed. The pin 9 is then inserted in the aperture 5 and allowed to project beyond the rear side thereof and in the path of the outward movement of the door, thus forming a stop adapted to engage the door and prevent its outward movement. Thus, it will be seen that we have provided a light, strong fastener of small size, the drawings showing the same greatly enlarged, which can be readily carried about the person; which will fasten any door of ordinary construction; and which is of such strength, and the manner of securing the same to the door and door jamb is such, that the fastening thus formed is very strong and will withstand a large amount of pressure applied to the door.

We wish it to be understood that we do not desire to be limited to the exact details of construction shown and described, for obvious modifications will occur to a person skilled in the art.

Having thus fully described our invention, what we claim as new and desire to secure by Letters Patent, is:—

A fastener of the character described comprising a plate having one end rounded and beveled on one side thereof, said plate being adapted to extend between the door and door jamb and having a projection extending therefrom on the side opposite the side having said 10 beveled edge at a distance from the end thereof and adapted to engage the face of said door jamb, a shoulder formed on said

plate on the side having said projection and adapted to engage the edge of said door jamb, and a removable stop adapted to extend through said plate in the rear of said shoulder and to engage the door. 15

In testimony whereof, we affix our signatures in presence of two witnesses.

BENJAMIN F. HUGHES.
FERDINAND A. PFEIFER.
